UNITED STATES PATENT OFFICE.

GLOVER ORIN PARKER, OF BENTONVILLE, ARKANSAS, ASSIGNOR OF ONE-THIRD TO TAYLOR THOMAS HARRIS, OF BENTONVILLE, ARKANSAS, AND ONE-THIRD TO WILLIAM M. SCOTT, OF BALTIMORE, MARYLAND.

SHIP PROPULSION AND THE LIKE.

1,268,765.

Specification of Letters Patent.

Patented June 4, 1918.

Application filed March 25, 1915. Serial No. 16,990.

To all whom it may concern:

Be it known that I, GLOVER ORIN PARKER, a citizen of the United States, residing at Bentonville, in the county of Benton and State of Arkansas, have invented certain new and useful Improvements in Ship Propulsion and the like, of which the following is a specification, reference being had therein to the accompanying drawing.

10 This invention relates to power development utilizable for various purposes, such as the propulsion of boats, aerial ships, aeroplanes, etc.

15 The object of the invention is to provide for the development of power for propulsion and other purposes, which consists in effecting movement of a power-creating instrumentality in a fluid in such manner as to create a force whereby a high degree of 20 momentum is produced.

25 A further object of the invention is to provide, in a simple and compact structure, an aggroupment of components adapted to be moved through a fluid, such as the atmosphere, water, etc., at least one of the components being movable in such manner as to develop a force upon the fluid, whereby the structure, in its entirety, may be propelled.

30 Still another object of the invention is to provide a structure comprising an aggroupment of instrumentalities, in one of which is housed driving mechanism adapted to be mechanically connected with the other instrumentality, constituting a driven component, so that the latter may be rotated in 35 a fluid in such manner that the fluid may pass through the driven component and develop a force for the propulsion of the structure through the fluid.

40 Broadly, the invention resides in a buoyant body and a revolving body having a discharge opening of greater diameter than the inlet, whereby the fluid may be introduced into the inlet and discharged at the 45 outlet at an augmented velocity.

More specifically, the invention resides in introducing a fluid into the smaller end of a frustrated cone and discharging it at the larger end thereof at an augmented velocity.

50 The invention seeks, in general, to provide for the propulsion of a buoyant body through a fluid at high speed, this being attained by rotating a hollow, frustrated cone and introducing a fluid into the smaller end

thereof and discharging said fluid at the 55 larger end at an augmented velocity.

Other objects and advantages are present in the invention and these will be obvious from the accompanying drawings and also from the following description.

60 In order that the invention may be comprehended, drawings are hereto appended which are illustrative of various possible embodiments and utilizations thereof; but it is to be understood that these are illustrative and that the invention is susceptible of a wide range of modification and is capable of embodiments and utilizations other than those disclosed.

65 In these drawings:

70 Figure 1 is a view in perspective of a boat with the invention applied thereto;

Fig. 2 is a view in vertical longitudinal section thereof;

75 Fig. 3 is a view, in longitudinal section, on an enlarged scale, of the propelling instrumentality, detached from the boat;

Fig. 4 is a view in vertical transverse section thereof;

80 Figs. 5 to 8 are detail views of certain modifications of the propeller; and

Fig. 9 is a view in perspective of an aeroplane provided with the invention.

85 In these drawings, the reference-numeral 1 designates the hull of a boat which, in this instance, is more or less cylindrical. The hull is provided with a cockpit 2 of any appropriate form and construction.

90 The rear portion 4 of the hull is preferably conical and considerably elongated, as shown. In practice, it is found to be of advantage to make the conical portion 4 hollow, and may be filled with ballast, if desired.

95 The forward portion 3 of the hull is in the form of a truncated cone and preferably is also hollow. Between the body portion of the hull and the front and rear portions 3 and 4 are bulkheads 5 and 6, of any desired kind.

100 The forward conical portion 3 also is provided with a bulkhead 7.

Disposed within the boat is an engine or motor 8 that may be of any appropriate character, and to this is attached a transmission shaft 9 which extends through the conical portion 3 and projects beyond the same.

Mounted on the forward end of the shaft is a propeller 10 that is of a particular construction: As shown in Figs. 1 to 3, which embody the invention in one of its aspects, 5 the propeller includes a frustrated cone, designated 11. Within this is mounted an internal frustrated cone 12. Between the two cones are division members 13. The shaft is secured to the inner cone, and the 10 division members constitute a rigid connection between the two cones. They also have additional functions which will presently be pointed out.

It is the desideratum of my invention to 15 introduce the fluid into the forward end 14 of the propeller 10 and discharge it at the rear end 15. It will be observed that this rear end of the cone is of a diameter greater than the conical portion 3 of the hull.

20 A rudder 16 is suitably disposed on the portion 4 and operated by the usual tiller-ropes 17 which are actuated by a hand-wheel 18 disposed in the cockpit 2.

The operation of the structure is as follows: The engine 8, having been started, the 25 propeller 10 is thereby set in motion, with the result that the fluid which has entered the forward end 14 thereof will move between the surfaces of the two cones 11 and 30 12 and between the division plates and discharge, in a tangential direction, at the rear end 15 of the propeller. In so doing, the fluid is impelled, with force, rearwardly and against the body of fluid which normally 35 would surround the conical portion 3. When the speed of the propeller and the flow of the fluid have reached a certain degree the impingement of the fluid that has flowed through the propeller effects a 40 active force on the fluid surrounding the portion 4, and this produces a high degree of momentum of the boat and propels it. There is a considerable displacement of the fluid from around the forward portion of 45 the boat resulting from the action of the fluid through the propeller, so that, as this fluid tends to move back against the hull, it will, with great pressure, encompass the conical portion 4 and, by its pushing effect 50 thereon, augment the action of the propeller in drawing the boat forward.

While, in the foregoing description, the 55 operation of the structure has been set forth in connection with the movement of a body through water as the fluid; yet it is to be understood that the invention is capable of being operated in the air, as the fluid. Therefore, in Fig. 9, the utilization of the 60 invention is disclosed in connection with an aeroplane. Generally speaking, the operation of the propeller, in this instance, is the same as that described in connection with the boat-structure.

In Fig. 5, there is illustrated a fluid-con- 65 trolling device that may, if deemed essential

or advisable, be mounted so that it will move through the fluid in advance of the propeller: This includes a conical casing 19 provided with a series of apertures 20 and disposed upon the forward end of the propeller itself. Mounted on the forward end of an inner shaft 22—the main shaft 23, in this instance, being hollow—is a conical member 21 adapted to be moved in relation to the inner walls of said member 19. 70 Means are provided for effecting its movement and these include a shaft-shifting mechanism 24 disposed within the cockpit and comprising a screw-shaft 25 rotatable in stationary bearings 26 secured in the 80 cockpit and adapted to actuate a bracket 27—into which the shaft is threaded—carried at the end of the shaft 25 and connected to a collar 28 which encircles the main shaft 23 and connects with the shaft 22. By this means, the shaft 22 may be given a longitudinal movement so that the conical member 21 can be positioned in relation to the inner walls of the cone 19. Its relative position with respect to said inner walls will 90 determine the amount of inflow of fluid into the cone 19 and, thus, into the propeller. If it is positioned against said inner surface, it will cut off all inflow and thereby prevent operation of the propeller. On the 95 other hand, if it is positioned remotely from said inner surface, a considerable volume of water can pass into the structure and, in this way, a large volume of water be introduced into the propeller, with consequent 100 augmented action thereof in the manner already explained.

In Figs. 6 to 8, modified forms of structure are illustrated: Fig. 6 shows a propeller having an elongated portion, with a conical 105 portion. In Fig. 7, there is disclosed a form of propeller in which the division members are curved, and whereby, under certain conditions, the action of the propeller is facilitated and the power thereby developed increased.

In Fig. 8, a propeller with an outwardly-flared curved surface is presented. In some instances, these modified forms of propellers may be found to be desirable and effective. 115

It is to be understood, as already pointed out, that the invention is susceptible of even greater modification; wherefore, it will be seen that what is herein disclosed is merely illustrative and is not to be regarded as indicating the limits of the invention.

What I claim is:

1. The combination of a vessel having a body, and a forward portion with sides which converge from the body, of a propeller located at the forward portion and comprising a cone-shaped casing, the narrow end thereof being the entrance end for a propelling medium, and the larger end being the discharge point therefor; said 120

wider end being in proximity to and of larger dimension than the forward portion of the vessel.

2. The combination of a vessel having a body, and a forward portion with sides which converge from the body to constitute a nose or bow truncated at its forward end; of a propeller located at the forward portion and comprising a cone-shaped outer casing; a casing disposed within the outer casing, the narrow end thereof being the entrance end for a propelling medium, and the larger end being the discharge point therefor; said wider end being in proximity to and of larger dimension than the truncated nose portion of the vessel.

3. In a vessel having a body or hull, and a bow or nose having sides which converge from the hull and which are truncated at the forward end thereof; a propeller located at the forward end of the vessel and comprising a truncated cone shaped outer casing; a similarly shaped casing disposed within the outer casing, the narrow end of said casings being forward and forming an entrance for a propelling medium, the other end of the casings being flared and of larger dimension than the truncated nose portion of the vessel.

4. In a vessel having a body or hull, and a bow or nose having sides which converge from the hull and which are truncated at the forward end thereof; a propeller located at the forward end of the vessel and comprising a truncated cone-shaped outer casing; a similarly shaped casing disposed within

the outer casing, the narrow end of said casings being forward and forming an entrance for a propelling medium, the other end of the casings being flared and of larger dimension than the truncated nose portion of the vessel and vane members disposed between the casings, the flared end of the casings being in spaced relation to the truncated nose portion of the vessel.

5. In a vessel having a body or hull, an elongated steam portion and a bow or nose portion in the form of a truncated cone the sides of which converge abruptly from the body or hull; a drive shaft passing through the bow; means for driving the shaft located in the vessel; a truncated cone shaped casing in spaced relation to the drive shaft and connected therewith; a similarly shaped casing disposed around and in spaced relation to the inner casing; vane members disposed within the casings; the smaller end of the casings being forward and forming an entrance for a propelling medium; the larger end of the casings being in spaced relation to the nose of the vessel and of larger dimension than said nose, whereby the propelling medium after passing through the casings will be given an outward deflection at an angle to the line of entrance thereto.

In testimony whereof I affix my signature in presence of two witnesses.

GLOVER ORIN PARKER.
